UNITED STATES PATENT OFFICE

171,644

BOTTLE HOLDER

Robert P. Etienne, San Mateo, Calif.

Application July 13, 1953, Serial No. 25,895

Term of patent 14 years

(Cl. D83—8)

To all whom it may concern:

Be it known that I, Robert P. Etienne, a citizen of the United States of America, resident of San Mateo, California, have invented a new, original, and ornamental Design for a Bottle Holder, of which the following is a specification, reference being made to the accompanying drawing forming a part thereof.

Fig. 1 is a front elevational view of a bottle holder embodying my new design; and

Fig. 2 is a side elevation of Fig. 1.

The back of my design is substantially plain, merely depicting the outline of an animal.

I claim:

The ornamental design for a bottle holder, substantially as shown and described.

ROBERT P. ETIENNE.
